DESIGN FOR A GUITAR OR SIMILAR MUSICAL INSTRUMENT

Fred Gretsch, Jr., Forest Hills, N. Y.

Application January 31, 1941, Serial No. 98,619

Term of patent 14 years

To all whom it may concern:

Be it known that I, Fred Gretsch, Jr., a citizen of the United States of America, residing at Forest Hills, county of Queens and State of New York, have invented a new, original, and ornamental Design for a Guitar or Similar Musical Instrument, of which the following is a specification, reference being had to the accompanying drawing, forming a part thereof.

or similar musical instrument, showing my design.

The dominant feature of my design resides in the portions shown in full lines.

I claim:

The ornamental design for a guitar or similar musical instrument, as shown and described.
